(57) **CLAIM**

The ornamental design for footwear upper, in any of the embodiments as shown and described.

DESCRIPTION

FIG. 1 is a perspective view of the footwear upper embodying the new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof; and

FIG. 7 is a perspective view of a second embodiment of the footwear upper embodying the new design;

FIG. 8 is a top plan view thereof;

FIG. 9 is a right side elevational view thereof;

FIG. 10 is a left side elevational view thereof;

FIG. 11 is a front elevational view thereof; and,

FIG. 12 is a rear elevational view thereof.

The broken lines and stitching in FIGS. 1-12 represent environmental structure and form no part of the claimed design in the respective embodiments.
